UNITED STATES PATENT OFFICE.

JOHN EVANS, OF PHILADELPHIA, PENNSYLVANIA.

HOT-AIR FURNACE.

SPECIFICATION forming part of Letters Patent No. 436,075, dated September 9, 1890.

Application filed March 20, 1889. Serial No. 304,075. (No model.)

To all whom it may concern:

Be it known that I, JOHN EVANS, a citizen of the United States, residing at Philadelphia, in the county of Philadelphia and State of 5 Pennsylvania, have invented certain new and useful Improvements in Hot-Air Furnaces, of which the following is a specification.

My invention has relation to hot-air furnaces having a direct draft from the combustion-chamber or fire-box to the smoke-flue for use in starting the fire and an indirect draft from the top of the combustion-chamber downwardly through the furnace and thence to the smoke-flue, such indirect draft being 10 employed after the fire is started and the direct draft is shut off for maintaining a uniform combustion, for obtaining an even distribution of heat in the furnace, and for utilizing such indirect hot-air draft before escap- 15 ing into the chimney for heating the cold-air supply for the furnace before such air comes into contact with the combustion-chamber, fire-box, or other like heated parts of the furnace, the intent being that such indirect draft from the furnace when passing into the smoke-flue shall be nearly devoid of heat, and consequently effecting an economy in the use of coal for heating large volumes of cold air.

My invention has for its object simplicity of construction of parts and their arrangement so as to increase the efficiency of the furnace, make it more durable, and to provide for easy access to its component parts 35 for cleaning or for repairing and replacing the same.

My invention accordingly consists of the combinations, constructions, and arrangements of parts, as hereinafter described in 40 the specification, and pointed out in the claims.

Reference is had to the accompanying drawings, wherein—

Figure 1 is a vertical section of a furnace 45 embodying my improvements, the coal-chute for the combustion-chamber being shown by dotted lines *y y*; and Fig. 2 is a horizontal section of the same on the line 1 1, Fig. 1, the top plate of the cold-air chamber being partly 50 broken away and its front side being partly in section.

A represents the furnace, consisting of the

usual outer casing *B*, the inner casing *C*, fire-box *D*, combustion-chamber *E*, hot-air drum *F*, direct-draft flue *f*, having damper *f²* and 55 connecting with the smoke-flue *H*, and cold-air chamber *G* at the bottom of said furnace. The latter consists of top and bottom plates *a a'* and suitable side and end plates *a² a³*, to form an oblong or rectangular shaped cold-air chamber, the end *g* of which extends beyond the furnace and has a vertical projection *g'* running up to near the top of the furnace, where it connects with a flue *g²*, which leads to the exterior of the building wherein 65 the furnace is located, in order to obtain a supply of fresh or pure air for the furnace.

The fire-box *D* may be of any suitable form, having the usual or other grate and ash-pit. The latter is located in the cold-air chamber 70 in the usual manner, as at *x*.

The combustion-chamber *E* may be of any suitable construction; but I prefer to provide it with a contracted outlet *e*, centrally located in its upper end plate *e'*, which is curved outward, as shown, for a purpose hereinafter to be described.

The outlet-pipe *e* connects with or leads into the hot-air drum *F*, which has part of its bottom plate inwardly curved, as at *f'*, to conform to or correspond with the curve of the combustion chamber top plate *e'*, so as to provide a space between said curved parts to direct ascending currents of air toward the outlet *e*, and in a measure momentarily retain said air in the recess formed by the inward-curved bottom part *f'* of drum *F*, in order to highly heat such air before it escapes from the furnace through one or more of the usual casing-outlets *A'* at the top of the fur- 90 nace.

Depending from the bottom of drum *F* are a series of vertically-arranged pipes *f³ f⁴*, which extend to, and connect with pipes *f⁵* and *f⁶*, respectively, located in the cold-air 95 chamber *G*. The pipes *f⁵* run longitudinally with the cold-air chamber *G* and are connected by the transversely-located pipe *f⁶*; and *f⁷* is another corresponding pipe connecting the rear ends of pipes *f⁵* and has at or near its center a connection with a pipe *f⁸*, which leads up to and connects with the smoke-flue *H*, said pipe *f⁸* and part of the flue *H* being incased in the vertical cold-air

flue g' , as shown more plainly in Fig. 1. The pipes f^5 , f^6 , and f^7 are separate from, but located and supported in, the cold-air chamber G. The pipe f^8 is provided with a suitably-located damper f^9 , which, as shown in Fig. 1, is located in said pipe below the direct-draft pipe f^2 or its connection with the smoke-flue H. The pipes f^5 are provided with suitably-formed removable covers f^{10} for their ends or other parts of the same, and in line therewith on the sides or ends of the cold-air chamber G are openings having doors or removable covers a^4 , by means of which access may be readily had to the said pipes in the cold-air chamber G for cleaning, repairs, replacement, or analogous purposes.

The operation of the heater or furnace is as follows: When the fire is to be started, the damper f^9 in pipe f^8 is closed and damper f^2 in pipe f is opened, the draft from combustion-chamber E is then through outlet e to drum F and through pipe f directly to the smoke-flue H, and such draft is the direct draft and is used until the fire is fully started, after which the damper f^2 is closed to shut off the direct draft and the damper f^9 is opened. The draft is then from drum F by way of the series of pipes f^8 f^4 to pipes f^5 f^6 f^7 and from the latter through terminal end or pipe f^8 to smoke-flue H, being the indirect draft-course between the combustion-chamber E and smoke-flue H. The cold-air supply emerging from flue g^2 passes down flue g' in contact with the pipe f^8 , absorbing the heat of the hot draft therein, so that said air-supply passes to cold-air chamber G in a heated condition to be still further heated by contact with pipes f^5 , f^6 , and f^7 before passing through the perforated or skeleton top plate a' to the chamber C', wherein is located the fire-box, combustion-chamber, and drum F, and as such air-supply when it enters chamber C' is well warmed or heated it is economically further heated by the radiated heat from the combustion-chamber E and drum F, so that a large amount or volume of such air can be warmed by the expenditure of much less coal than has heretofore been used. As the air-currents ascend in chamber C' more or less of the same are conducted into the curved space between the bottom of drum F and top of combustion-chamber E to be momentarily retained at the hottest part of the drum for highly heating the same. As the cold-air supply entering flue g' has to contact with an extended length of indirect-draft-flue terminal end f^8 and with an extended area of such flue-pipes f^5 , f^6 , and f^7 , in chamber G, ample time and facility are provided to admit of such cold air absorbing all

the heat from the hot air in said flues, so that as it escapes into the smoke-flue H it is comparatively cold.

In practice with a heater or furnace constructed as above described, I find that part 65 of the smoke-flue H beyond the cold-air flue g^2 to be cold, and but one supply of fuel for the furnace per day is all that is needed to warm or heat sufficient air to thoroughly heat the building wherein the furnace is located 70 for the entire day.

From the foregoing it will be noted that the ash pit or box x is located in the cold-air chamber G, and the indirect-draft flues f^5 f^6 are so located as to embrace or surround 75 the inner sides of the ash-pit, in order to give extended length of radiating-surface to said pipes or flues. Furthermore, the location of said ash-pit and pipes or flues in the cold-air chamber G admits of a compact form 80 of heater or furnace in height which is suitable for use in the usual restricted cellar-heights of small buildings.

What I claim is—

1. In a hot-air furnace, the combination of 85 a combustion-chamber, a cold-air chamber below the level of the combustion-chamber and having an end extending beyond the furnace, a vertical extension or flue from said end leading to the cold-air-inlet flue, a smoke-pipe 90 in said vertical flue leading down to the cold-air chamber, an ash pit or box in the cold-air chamber, a series of tubular flues in said chamber surrounding or extending around the three sides of the ash-pit in said chamber, and flue-connections between the combustion-chamber and the tubular flues in the cold-air chamber and between the latter and the said smoke-flue, substantially as shown and described.

2. In a hot-air furnace, the combination of 100 a combustion-chamber, the smoke-drum F, cold-air chamber G, below the level of said combustion-chamber, having an outside vertical flue g' , an ash-pit, and a series of horizontally-located smoke-flues f^5 , f^6 , and f^7 in 105 said cold-air chamber, said smoke-flues f^5 , f^6 , and f^7 being separate from and extending around the three sides of the ash-pit in chamber G, flues f^8 , connecting drum F and pipes 110 f^5 , f^6 , and f^7 , and a smoke-flue f^8 , leading from the latter through flue g' , substantially as set forth.

In testimony whereof I affix my signature in presence of two witnesses.

JOHN EVANS.
